UNITED STATES PATENT OFFICE.

JAMES CHRISTY, OF CLEVELAND, OHIO, ASSIGNOR TO THE PORTAGE RUBBER COMPANY, OF BARBERTON, OHIO, A CORPORATION.

DESIGN FOR A VEHICLE-TIRE.

48,485.

Specification for Design.

Patented Feb. 1, 1916.

Application filed October 18, 1915. Serial No. 56,613. Term of patent 14 years.

To all whom it may concern:

Be it known that I, JAMES CHRISTY, a citizen of the United States, residing at Cleveland, county of Cuyahoga, and State of Ohio, have invented a new, original, and ornamental Design for a Vehicle-Tire, of which the following is a specification, reference being had to the accompanying drawing, forming part thereof.

I claim:

The ornamental design for a vehicle tire, as shown.

JAMES CHRISTY.
